(57) **CLAIM**

The ornamental design for a case for electronic communications device, as shown and described.

DESCRIPTION

FIG. 1 is a front perspective view of a case for electronic communications device showing my new design;
FIG. 2 is a rear perspective view thereof;
FIG. 3 is a front elevational view thereof;
FIG. 4 is a rear elevational view thereof;
FIG. 5 is a left side elevational view thereof;
FIG. 6 is a right side elevational view thereof;
FIG. 7 is a top plan view thereof;
FIG. 8 is a bottom plan view thereof;
FIG. 9 is an enlarged detail view of the encircled region from FIG. 2;
FIG. 10 is an enlarged detail view of the encircled region from FIG. 4; and,
FIG. 11 is a cross-sectional view of the case for electronic communications device taken along the line 11-11 of FIG. 4. The dash-dot broken line circle in FIGS. 2 and 4 delineates a portion of the case for electronic communications device that is part of the claimed design and that is shown on an enlarged scale respectively in FIG. 9 and FIG. 10.
